UNITED STATES PATENT OFFICE.

MAX C. MILLER, OF CUMBERLAND HILL, RHODE ISLAND, ASSIGNOR TO JENCKES
KNITTING MACHINE COMPANY, OF PAWTUCKET, RHODE ISLAND, A CORPORATION
OF RHODE ISLAND.

WEB-HOLDER MECHANISM FOR KNITTING MACHINES.

Original application filed April 5, 1921, Serial No. 458,640. Divided and this application filed May 27, 1922. Serial No. 564,211.

To all whom it may concern:

Be it known that I, MAX C. MILLER, a citizen of Germany, residing at Cumberland Hill, in the county of Cumberland and State 5 of Rhode Island, have invented certain new and useful Improvements in Web-Holder Mechanism for Knitting Machines; and I do hereby declare the following to be a full, clear, and exact description of the invention, 10 such as will enable others skilled in the art to which it appertains to make and use the same.

The invention relates to mechanism for actuating the web holders of circular knitting machines such as are used for knitting seamless hosiery.

The object of the invention is to provide simple and efficient mechanism which is well adapted for retracting the web holders as 20 they approach the knitting point and for advancing them at the knitting point during reciprocatory knitting without danger of over-driving at the knitting point and without idle advance of the web holders prior to 25 their withdrawal tending to strain the stitches and vibrate the idle needles. To these ends the invention comprises the features of construction and combination of parts hereinafter described and referred to 30 in the claims.

The present application is a division of application Serial No. 458,640, filed April 5, 1921, and a preferred form of the invention applied to the machine which is fully shown 35 and described in said application is shown in the drawings. Fig. 1 is a detailed sectional view showing so much of the needle cylinder as is necessary to indicate the application of the present invention thereto, and 40 Fig. 2 is a plan view showing the web holder actuating cams and the controlling devices therefor.

The machine indicated in the drawings is 45 provided with a rotating and reciprocating needle cylinder 2 in which the needles 4 are mounted in the usual manner. The web holders 6 are mounted to slide radially in a dial 8 secured to the upper end of the needle cylinder and are provided with butts 10 which engage a concentric groove 12 formed in a web holder cam ring 14 and are acted on by advancing and retracting cams arranged at a gap in the groove. The cam

ring is provided with two advancing cams 16 and 18 for advancing the web holders 55 at the knitting points during rotary and reciprocatory knitting, and with two retracting cams 20 and 22 for withdrawing the web holders as they approach the knitting points. The cams 20 and 22 are rigidly connected with the cams 18 and 16 and are spaced therefrom to form a guideway for the web holder butts which positively controls their movements and prevents over-driving of the web holders under the action 60 of the advancing cams. The two sets of cams are carried on the inner ends of two movable cam carrier levers 24 and 26 which are pivoted at 28 and 30 to the web holder cam ring and are pressed outward by springs 65 32. Each set of cams is thus radially movable and its active position is determined by one of two stationary controller cams 34 and 36 adjustably supported upon a fixed bracket 38. The controller cams are so arranged that when the cam ring is in position for rotary knitting the lever 24 will be in engagement with the controller cam 34 and the advancing cam 16 will be held in active position while the lever 26 will be pressed outward by its spring to hold the advancing cam 18 out of active position and the retracting cam 22 in position to retract the web 70 holders preparatory to their advance by the active advancing cam 16. When the cam ring is shifted on a reverse stroke of the needle cylinder in reciprocatory knitting the lever 26 will be carried into engagement with its controller cam 36, thus forcing the advancing cam 18 into active position while the lever 24 will be disengaged from its controller cam and will be moved outward by its spring to withdraw the advancing cam 16 from active position and to project the retracting cam 20 into active position. The 75 inactive advancing cam will thus be withdrawn slightly from active position so that the web holders will not be advanced in passing the point of the cam prior to their withdrawal by the opposed retracting cam and will not, therefore, press against and strain the stitches or tend to vibrate the inactive needles as they approach the throat through which the yarn is fed to the needles. 80

The controller cams are so shaped that 85 when the needle cylinder is raised or lowered 90

to lengthen or shorten the stitch they will vary the radial position of the active web holder advancing cam so that the advance movement of the web holders will be varied 5 in accordance with the variations in the

length of stitch. This construction and mode of operation corresponds generally to that shown, described and claimed in applications numbered 250,361 and 250,362, filed

10 August 17, 1918.

While it is preferred to employ the specific construction and arrangement of parts shown and described in embodying the invention in the machine of the application 15 above referred to it will be understood that this construction and arrangement is not essential to the broader features of the invention and may be varied or modified as found desirable or best suited to the construction 20 and mode of operation of the machine to which it is to be applied.

What is claimed is:

1. A knitting machine having, in combination, a needle cylinder, web holders, a 25 web holder cam ring, a cam carrier movable on the ring toward and away from its axis, and a web holder advancing cam and a web holder retracting cam in fixed relation on the carrier, and means for advancing and 30 retracting the carrier during the knitting.

2. A knitting machine having, in combination, a needle cylinder, web holders, a web holder cam ring, two cam carriers movable on the ring toward and away from its axis, 35 a web holder advancing cam and a web holder retracting cam in fixed relation on each carrier, and means for alternately advancing and retracting the carriers during reciprocatory knitting.

40 3. A knitting machine having, in combination, a needle cylinder, web holders having butts, a web holder cam ring, a cam carrier movable on the ring toward and away

from its axis, a web holder advancing cam on the carrier, and a web holder retracting 45 cam on the carrier spaced to form a guideway for the butts at the point of the advancing cam.

4. A knitting machine having, in combination, a needle cylinder, web holders having butts, a web holder cam ring, two cam carriers movable on the ring toward and away from its axis, a web holder retracting 50 and a web holder advancing cam on each carrier spaced to form a guideway for the 55 butts.

5. A knitting machine having, in combination, a needle cylinder, web holders having butts, a web holder cam ring, two levers pivoted to move on the ring toward and 60 away from its axis, and a web holder advancing and an opposed web holder retracting cam on each lever spaced apart to form a guideway between them for the butts.

6. A knitting machine having, in combination, a needle cylinder, web holders, a web holder cam ring, a cam carrier movable on the ring toward and away from its axis, a web holder advancing cam and a web holder retracting cam in fixed relation on 70 the carrier, and a controller cam acting on the carrier to control its position during the knitting.

7. A knitting machine having, in combination, a needle cylinder, web holders, a web holder cam ring, two cam carriers movable on the ring toward and away from its axis, a web holder advancing cam and a web holder retracting cam in fixed relation on each carrier, controller cams for alternately 80 advancing and retracting the carriers during reciprocatory knitting and for varying the radial position of the active web holder advancing cam in accordance with the length of stitch.

MAX C. MILLER.
